(57) **CLAIM**

The ornamental design for a fuel dispenser payment device, as shown and described.

DESCRIPTION

FIG. 1 is a front perspective view of the fuel dispenser payment device;

FIG. 2 is a front view of the device;

FIG. 3 is a rear view of the device;

FIG. 4 is a side view of the device;

FIG. 5 is a side view of the device;

FIG. 6 is a top view of the device; and,

FIG. 7 is a bottom view of the device.

The broken lines in the drawings depict portions of the fuel dispenser payment device that form no part of the claimed design.

The unshaded surfaces shown between the solid lines and the broken lines form no part of the claimed design.

1 Claim, 5 Drawing Sheets(56)
